UNITED STATES PATENT OFFICE.

WILLIAM A. FRASER, OF BROOKLINE, MASSACHUSETTS.

COLLAPSIBLE SHIELD.

1,385,371.

Specification of Letters Patent. Patented July 26, 1921.

Application filed September 13, 1918. Serial No. 253,878.

To all whom it may concern:

Be it known that I, WILLIAM A. FRASER, of Brookline, in the county of Norfolk and State of Massachusetts, have invented a new 5 and useful Collapsible Shield, of which the following is a specification.

My invention relates principally to shields for military purposes and especially to shields for the breast.

10 One object of my invention is to provide a shield which, when not in use, is collapsible into very compact form, this compactness being a very important characteristic of my shield. Another object is to provide 15 a shield which is extremely light but which is at the same time preferably bullet proof and bayonet proof.

A feature of my invention consists in constructing my shield of a plurality of members, each being slidably mounted on the adjacent member.

20 Another feature consists in having the joints between adjacent members entirely covered at the front so that no opening is 25 available for penetration, whether by a bayonet or bullet, or otherwise.

Another feature consists in having the guiding portions of adjacent members out 30 of line so that the easy sliding into collapsible form is not interfered with.

Other features will be pointed out below. In the drawings—

Figure 1 is a front elevation of a shield extended and embodying my invention;

35 Fig. 2 is a front elevation of the same in position on the user;

Fig. 3 is a rear elevation of said shield extended;

Fig. 4 is a rear elevation of the central 40 member and of the members at one side of the shield, the members being separated;

Fig. 5 is a front elevation of the members shown in Fig. 4;

Fig. 6 is a section on line 6—6 of Fig. 3 45 but on a larger scale;

Fig. 7 is a similar section but showing the members in the position of actual use;

Fig. 8 is a section on line 8—8 of Fig. 3;

Fig. 9 is a rear elevation of the shield in 50 collapsed form;

Fig. 10 is a partial front elevation of a modification;

Fig. 11 is a partial section of said modification;

55 Fig. 12 is a front elevation of another form; and

Fig. 13 is a side elevation of the form of Fig. 12.

The central member of my shield has a central reinforcing rib α and a portion at 60 one side bent into outer or front part α' and inner part α'' the latter having guiding slits α^3 and α^4 , said parts being substantially parallel and the slits being protected by the part α' . At the other side of said rib the 65 central member has similar parts α^5 and α^6 and similar slits α^7 and α^8 .

The member adjacent to portion α^2 has front part b and rear part b' , said parts being bent substantially parallel, and the part 70 b having portion b^2 partially cut out so that it may be bent up and passed through slit α^3 and then its ends b^3 and b^4 are bent substantially parallel with part α^2 , the shank part 75 b^5 of portion b^2 acting in slit α^8 to guide part b with relation to part α^2 , thus providing relative sliding movement which is limited by the ends of slit α^8 . Similarly portion b^6 cooperates with slit α^4 . These joints are completely covered at the front by part 80 α' . The part b' has slits b^7 and b^8 to cooperate with partially cut out portions d and d' of the outer part d^2 of the next member whose inner part d^3 is slotted at d^4 and d^5 to receive partially cut out portions e and e' 85 of the next member and so on, the joint of the inner part of any member being completely covered by the outer part of that member. This joining feature is partially, although sufficiently, illustrated in Fig. 8 in 90 which the slit f receives partially cut out portion g and slit g' receives partially cut out portion h of the end member, the latter having perforations or slits h^1 and h^2 to receive the ends of elastic cloth strap k which 95 is provided with a metal loop k^1 connected to a hook k^2 which engages ring k^3 , the latter being similarly connected to similar straps k^4 and k^5 , the ends of strap k^4 passing over the user's shoulders and being connected to the central member at the slits k^6 and k^7 and the ends of strap k^5 passing around the user's side and engaging the slits k^8 and k^9 , thus furnishing a quick means of fastening my shield in place and providing for 100 yielding movement and providing also that the ring k^3 may move about if necessary.

All the members are preferably of bullet proof metal and I cut away the inner parts as at l in order to make the whole shield very 105 light in weight, this cutting away not interfering in any way with the required

strength. I preferably make the center member and the members on each side of it somewhat higher than the other members and slope the members as shown so as to give the greatest freedom to the arms of the user, particularly for bayonet defense.

I preferably have the upper slits of adjacent members out of line along the shield, one purpose being to prevent interference 16 of the cut-out portion *e*, for example, with the opening in member *d*² left by cut-out portion *d*.

The series of members at the left of the center member in Fig. 3 are reversed but 15 otherwise are the same as the series consisting of members *b*, *d*², *e*², *f*², *g*² and *h*³.

When the shield is to be collapsed the two series of side members are rapidly slid in toward the center of the device until they 20 occupy the position shown in Fig. 9 forming an extremely compact structure and one readily packed for transportation either by itself or in quantities. In Fig. 11 I show a modification in which the two parts *m* and 25 *m'* of the center member are hinged together at *m*² and in this form one collapsed half of the shield at one side of the hinge may be folded over against the other collapsed half making the whole collapsed shield half as 30 wide as in the form of Fig. 9 but twice as thick.

In Fig. 12 I show a shield embodying my invention adapted to rest upon the ground and having a plurality of members slidably 35 connected as before described, each of the end members having riveted to it a spring leg *n* which legs support the shield as shown in Fig. 13, and when not in use are held close to the shield by spring catches *n*' *n*'. This 40 form is particularly adapted for machine gun work, the projectile passing through aperture *n*², and the shield being preferably made of bullet and bayonet proof material as above described.

45 One important feature of my shield is that it will fit a man of any size. Another important advantage is that, as shown in Fig. 7, when the shield is in use, the projectile will be efficiently deflected by reason of 50 the convex form of the front of the shield, the latter being preferably curved when in use for such deflection and to fit the body of the user.

Still another advantage is that the straps 55 may be wound around the shield to hold it in collapsed form.

What I claim is:

1. A shield comprising a plurality of substantially flat members, adjacent members 60 being movably joined together, the joint permitting expansion and collapse of said members crosswise of the wearer, and permitting said members to be parallel when collapsed but permitting them to be out of parallelism when the device is expanded

and the outer ends are pulled inwardly toward the wearer.

2. A shield comprising a plurality of outwardly exposed shield members, adjacent members being formed with integral portions coöoperating to form a sliding joint between such adjacent members, the joint permitting expansion and collapse of said members crosswise of the wearer and permitting said members to be parallel when collapsed 70 but permitting them to be out of parallelism when the device is expanded and the outer ends are pulled inwardly toward the wearer.

3. A shield comprising a plurality of members, each member having an outer 80 shielding part and an inner part connected to the outer part the inner part having a slideable connection with the outer part of the adjacent member said connection permitting expansion and collapse of said 85 members.

4. A shield comprising a plurality of members each member having an outer shielding part and an inner part having a swinging connection with the outer part, 90 adjacent members being movably joined together to permit expansion and collapse of the device and said swinging connection permitting said members to be parallel when collapsed but permitting them to be out of 95 parallelism when the device is expanded and the outer ends are pulled inwardly toward the wearer.

5. A shield comprising a plurality of members each having an outer and an inner 100 part and each member being movably joined to the adjacent member by said inner part, said joint being covered by said outer part.

6. A shield comprising a center member 105 having an outer part and two inner parts, each of said inner parts being slidably connected to one of a series of members and said connections being covered by said outer part, each of said series comprising a plurality of members, adjacent members of said plurality being slidably connected to each other, and said last-mentioned connections being entirely covered by outer parts of the members of said series.

7. A shield comprising a plurality of members, each member having an outer shielding part and an integral inner part having a swinging connection with the outer part, the outer part of one member and the 120 inner part of an adjacent member being formed, one with a slit and the other with an integral headed shank, to provide a sliding connection to permit expansion and collapse of the device and said swinging connection permitting said members to be parallel when collapsed but permitting them to be out of parallelism when the device is expanded and the outer ends are pulled inwardly toward the wearer.

8. A shield comprising a plurality of members, each formed of substantially parallel parts joined at the edge toward the center of the shield and open at the opposite edge, adjacent members being slidably connected. 25
9. A shield comprising a plurality of members, adjacent members being slidably connected and the connection between any 10 one member and the member adjacent it at one side being out of line with the connection between said one member and the member adjacent to it at the other side, said connection permitting rectilineal movement 15 crosswise of the user.
10. A device of the character described comprising a shield; and means to hold the shield in position including a member at the back of the user and portions extending 20 around the sides and over the shoulders of the user, said portions being connected to said member but having play with relation thereto.
11. A shield comprising a plurality of members, adjacent members having a sliding joint including a slit, said joint being covered at the front of the device when the latter is expanded, said joint permitting expansion and collapse of the device. 25
12. A shield comprising a plurality of 30 members, adjacent members having a sliding joint including a slit, said joint being covered with relation to the front of the device by one of said members when the device is expanded, said joint permitting expansion and collapse of the device. 35
13. A shield comprising a central member; a plurality of members expandable crosswise of the device in one direction with reference to the central member; and another plurality of members expandable crosswise of the device in the opposite direction with reference to the central member. 40

WILLIAM A. FRASER.
